Patented Dec. 4, 1928.

UNITED STATES PATENT OFFICE.

EDWARD HUTCHENS, OF MILWAUKEE, WISCONSIN.

WASHER-SETTER SPOUT.

Application filed April 2, 1926. Serial No. 99,218

This invention relates to a washer placing mechanism with special reference to setting washers onto the pins of rubber heel molds. It is an object of this invention to provide an improved form of distributing or placing mechanism for the washers embedded in rubber heels. This placing mechanism is a development of the washer sorting and placing mechanism as a whole, which has been more fully described in my co-pending application, Serial No. 81,668, filed January 16th, 1926 which has become Patent 1,681,480. The present application is confined to improvements in positioning or placing fingers which actually deposit the washers on the mold pins.

The washers themselves are frequently imperfect or burred and the burrs would interfere with the free flow of washers through the chutes and depositing mechanism, resulting in occasional clogging. If the chutes were made large enough to pass burred washers, jamming or clogging would be apt to occur by reason of the washers overlapping each other in the chutes. I have found that I can prevent overlapping of the washers without jamming due to burrs thereon, by providing a narrow strip forming the sole bearing member on either the top or the bottom of the washers, the extra space on either side of the strip providing sufficient room for burrs.

It is also an object of this invention to provide an improved positioning or depositing mechanism adapted to prevent washers from jarring out of the positioning fingers. Loose extra washers in rubber heel molds are a prolific source of trouble to shoe manufacturers because of the damage done thereby to the trimming knives used in shoe manufacture.

Other and further important objects of the invention will be apparent from the disclosures in the specification and accompanying drawings.

The invention (in a preferred form) is illustrated in the drawings and hereinafter more fully described.

On the drawings:

Figure 1 is a side elevation of a complete washer sorting and positioning mechanism embodying the features of this invention.

Figure 2 is a top plan view thereof.

Figure 3 is an enlarged fragmentary plan view with the presser feet omitted of the washer placing fingers in use on a heel mold.

Figure 4 is a fragmentary top view of the preferred form of central finger positioning mechanism.

Figure 5 is a section on the line V—V of Fig. 4.

Figure 6 is a section on the line VI—VI of Fig. 5.

Figure 7 is a fragmentary top view of one of the side fingers with the presser foot removed.

Figure 8 is a bottom view of Fig. 7.

Figure 9 is a side elevation of a modified form of center finger.

Figure 10 is a fragmentary top plan view thereof.

Figure 11 is a section on the line XI—XI of Fig. 9.

Figure 12 is an enlarged section showing the attachment of the wheels to the axles.

As shown on the drawings:

The sorting mechanism is shown only in outline for the reason that it differs from that described in my previously mentioned co-pending application only in that a pair of axles 15 carry wheels 16 which are adjustably mounted thereon to care for varying sizes of heel mold impressions, the wheels being spaced sufficiently apart to straddle the heel mold impressions 17 commonly provided on mold plates 18 as shown in Figure 3. This figure also clearly shows the mold pins 19 and washers 20 positioned thereon. The positioning fingers of the present invention will interchangeably handle either plain cupped washers as shown, or flanged washers of the same diameter, as the guides of the fingers are adjustable for different washer heights.

The sorting mechanism shown in outline comprises a sorting cylinder 21 mounted at the apex of a triangular frame 22, the base 23 of which carries the axles 15 and a central guideway 24 adapted to straddle the central pins of a row of heel mold impressions. A driving motor 25 for the sorting cylinder 21 is mounted within the frame and the driving connections therefrom are enclosed in the casing 26 shown in Fig. 2. A feeding hopper 27 for supplying the sorting cylinder is also shown in Figs. 1 and 2.

One of the outlets from the sorting cylinder is shown at 28 in Fig. 5, a washer finger 105 29 abutting thereagainst with the chute 30 therein aligned with the outlet 28, alignment being maintained by the tongue and

groove 31. The finger 29 shown in Figs. 3 to 6 inclusive, is divided underneath to receive an inserted narrow strip 32 which serves as a rail to support the washers above the bottom of the chute 30 to provide clearance for possible burrs on the washers. This strip or rail is clamped in place by the screws 33 and is adjustable up and down relative to the chute 30 to provide for different kinds and sizes of washers. The discharge or positioning end of the finger 29 is provided with an applied shoe 34 having two depending walls 35 providing an inclined passage 36 for the mold pins, the finger shoe sliding over the pins and being lifted slightly thereby; the passage 36 curving upwards abruptly to enter the chute 30 so that the finger and shoe drop suddenly when the mold pin reaches the point. The side flanges of the chute 30 are cut down at this point to allow the washer to be lifted from the chute, shoulders 37 being provided on the upper sides of the shoe walls to form stops for the lowermost washer in the chute, the washer being lifted out of these stops by the downward movement of the shoe when it drops over the pin. These shoulders are so positioned that the central hole of the washer is aligned with the mold pin so that the pin enters the washer hole at the same time it lifts the washer out of the shoe and chute. The washer is prevented from prematurely jarring out of the shoe by means of the side springs 38 having inwardly projecting ends bearing on the washer, the springs being distorted to produce the required pressure by means of the screws 39. A forked presser foot 40 is rigidly mounted above the chute and shoe and is intended to force the washer down over the pin, the forks of the foot being intended to bear unyieldingly and evenly on both sides of the washer. The side chute fingers 41, shown in Figs. 7 and 8, differ from the foregoing only in the provision of a special shoe 42 having only one depending wall 43 on the outside of each finger, the wall extending outwardly as a plow 44 adapted to draw the finger outwardly over mold pins spaced at varying distances from the center row of pins which serve as a guide for the machine as a whole.

In the modification shown in Figs. 9 to 11 inclusive, the finger 45 has a solid bottom chute 46 with the rail 47 suspended thereover to bear on the tops of the washers, thus leaving plenty of room on each side of the rail for irregularities in the washers. With this construction, as with the form of finger described hereinbefore, various shapes of washers can be accommodated by adjusting the position of the rail. In this form, the presser foot 48 is formed as a continuation of the rail 45 instead of being an additional mem-

ber, as with the presser foot 40 shown in Figs. 4 to 8.

I am aware that many changes may be made and numerous details of construction may be varied through a wide range without departing from the principles of this invention, and I therefore do not purpose limiting the patent granted hereon otherwise than necessitated by the prior art.

I claim as my invention:

1. In a machine of the class described, washer feeding mechanism, washer chutes fed thereby having a narrow rail defining one side of the chute, and washer placing mechanism associated with said chutes comprising shoulders at the end of said chutes, side springs having bearings on the foremost washer in contact with said shoulders, and guiding means positioned beneath said chute adapted to lift and drop the chute over a mold pin with said mold pin projecting through the washer hole.

2. Washer positioning mechanism comprising washer chutes, narrow rails associated with said chutes adapted to prevent overlapping of the washers therein, and means for adjustment of said rails to care for varying thicknesses of washers.

3. In a device of the class described, washer chutes having a slot for the washers of greater depth than the thickness of the washers to be handled and a vertically adjustable narrow central rail adapted to take up the excess depth of the slot to prevent washers from overlapping in the slot while providing excess clearance in the slot on both sides of the rail.

4. In a device of the class described, washer chutes having extra depth channels for washers and a rail centrally positioned in said channel adapted to reduce the available depth of the channel to prevent the washers from overriding.

5. In a device of the class described, washer feeding mechanism, a washer chute fed thereby, and washer placing mechanism associated with said chute including shoulders at the end of the chute for supporting the lowermost washer in the chute, side springs urged inwardly toward each other and downwardly into contact with the lowermost washer to hold it on said shoulders, guiding means positioned beneath said chute adapted to lift and drop the end of the chute over a mold pin with said pin projecting through said washer and a presser foot for holding said lowermost washer in place during said lifting and lowering of the chute.

In testimony whereof I have hereunto subscribed my name.

EDWARD HUTCHENS.
